DESIGN FOR A COMBINATION LIP STICK CONTAINER AND MIRROR

George E. Ball, Cranston, R. I.

Application August 28, 1935, Serial No. 58,346

Term of patent 7 years

To all whom it may concern:

Be it known that I, George E. Ball, a citizen of the United States, residing at Cranston, in the county of Providence and State of Rhode Island, have invented a new, original, and ornamental Design for a Combination Lip Stick Container and Mirror, of which the following is a specification, reference being had to the accompanying drawings, forming part thereof, in which:

Fig. 1 is a bottom perspective view of the combination lip stick container and mirror, showing my new design;

Fig. 2 is a top plan view thereof;
Fig. 3 is a side elevation thereof;
Fig. 4 is a bottom plan view thereof looking directly into the mirror; and
Fig. 5 is an end elevation thereof.

I claim:

The ornamental design for a combination lip stick container and mirror, as shown and described.

GEORGE E. BALL.
